UNITED STATES PATENT OFFICE.

WILLIAM C. CUTLER, OF NORTH GLENDALE, CALIFORNIA.

CARD-CASE.

1,296,484.

Specification of Letters Patent.

Patented Mar. 4, 1919.

Application filed June 27, 1917. Serial No. 177,264.

To all whom it may concern:

Be it known that I, WILLIAM C. CUTLER, a citizen of the United States, residing at North Glendale, in the county of Los Angeles and State of California, have invented new and useful Improvements in Card-Cases, of which the following is a specification.

My invention relates to devices for holding cards in a case and allowing cards to be taken out of the case one at a time.

One object of the invention is to have the cards in a case in such a position as to make it easy to take the cards out of the case one at a time.

Another object is to provide means by which the cards are placed into such a position as to allow the taking out of the cards one at a time one after another without having to operate any mechanism after the card case has been opened once.

Still another object is to provide means connected to the card case so as to operate the card holding means for placing the cards into such a position as to allow the taking out of cards one at a time one after the other without having to operate any mechanism after the card case has been opened once.

Other objects will appear in the following description and in the appended claims as well as in the accompanying drawing, in which—

Figure 1 is a cross section through a card case with my device in position.

Fig. 2 is a side elevation of the device inserted into the card case of Fig. 1.

Fig. 3 is a cross section of a card case with the inserted device slightly modified.

Fig. 4 is a cross section of a card case with still another modified construction of my device inserted.

Similar numbers refer to similar parts throughout the papers.

In Fig. 1, the numerals 6 and 7 designate the two opposing halves of a card case which are hingedly connected at 8. A frame, consisting of the base bar 9, the end bars 10, the side bars 11 and the spring members 12, as is more clearly illustrated in Fig. 2, is inserted into the card case of Fig. 1, the lower ends 13 of the frame being suitably formed to engage with the hinge 8 of the case, as will easily be understood. The end bars are provided for holding the cards endwise slightly pressing on the ends of the cards so as to loosen a newly inserted pack of cards enough to prevent an adhering of

the cards, one to another to insure the grasping of one card at a time. The end bars prevent also a slipping out of the cards endwise from the card case, being also strong enough to press against the edges of the cards with sufficient force to prevent the cards from falling laterally. The side bars are provided for holding the cards together in an upright position in the case, when opened, forming at the same time spring members for opening the case. The spring members 12 are provided for holding the frame with the cards in about the middle between the opposing halves of the card case when the case is open so that the cards may easily be taken out of the case.

In Fig. 3 is a slightly modified construction of the frame in my device, the side bars 11 of the frame being hingedly mounted on the base bar 9 at 14, and one of the side bars is provided with an extension end 15 projecting upwardly terminating in a bent end 16. In this construction, the end bars 10 alone press against the edges of the cards when the case is open to prevent the cards from falling laterally, the side bars 11 in this modified construction serve only to automatically open the case when the case is unlocked (by the usual locks in such cases, not shown in the drawing).

The spring members 12 naturally are bent to bring the inserted frame and especially the base bar 9 to the inclined and shifted position, illustrated in Fig. 1, when the card case is fully or a suitable distance opened. In compressed position, when the case is closed, the spring members on both sides of the base bar 9 are pressed toward the bar by the closing case. The spring members on the right hand side in Figs. 1 and 3 naturally are more compressed when in closed position as illustrated in Fig. 3 than the spring members on the left hand side, since the spring members at the right project almost at right angles from the base bar when in open position as illustrated in Fig. 1, while the spring members at the left almost retain the same position in open and closed position.

In closing this case, the extension end 15 with the bent end 16 naturally engages with the card case and thereby pushes the side extensions 17 of the base bar 9 to a practically horizontal position, as illustrated in Fig. 3. The ends of the base bar 9 are in this construction naturally pivotally mounted

between the end bars 10 at 21, the end bars being made in one piece from the hinge-connection 8 up to the top end 22. The bent end 16 serves to bring the cards back to the 5 squarely packed position shown in this figure from the shifted position illustrated in Fig. 1, in case that the cards should not go back with the frame when the frame is pushed by the extension end 15.

10 In Fig. 4, another slightly modified construction of my frame, the base bar of the frame is also pivotally mounted at 21 between the end bars 10 of the frame. The shifting of the frame in this slightly modified construction from the position shown in this figure to an inclined position as illustrated in Fig. 1 is accomplished by the connecting rod 18, which is pivotally connected to the base bar 9 of the frame at 19 and to 15 the case at 20.

Bringing the cards to the inclined position shown in Fig. 1, makes it easy to take out all the cards, one at a time, one after the other without having to operate any shifting mechanism. The top edge of the first card is naturally a suitable distance above the edge of the next card so as to make it easy to separate the first card from the rest for the purpose of taking it out of the case, as will 25 30 easily be understood. The shifting back of the cards to a squarely packed position has the advantage that the case does not have to be much larger than the cards, while the shifted cards would naturally require a case 35 so much larger as the first card projects above the last card.

Having thus described my invention, I claim:

1. In a card case of the class described a 40 frame comprising a base bar, end- and side-bars pivotally connected to the base bar, and spring members provided on the base bar projecting toward the case for shifting the base bar into a suitably inclined position 45 when the case is open.

Copies of this patent may be obtained for five cents each, by addressing the "Commissioner of Patents, Washington, D. C."

2. In a card case of the class described a base bar, end- and side- bars pivotally connected to the base bar, and an extension end formed on one of the side bars projecting beyond the uppermost edges of the inserted cards engaging with the case for bringing the cards to a squarely packed position when the case is closed. 50

3. In a card case of the type described a frame comprising base- end- and side- bars, 55 pivot interengaging means between the base- end- and side- bars and between the frame and the case, an extension end provided on one of the side bars slidingly engaging with the case for operating the frame on the hinge connections in relation to the case for bringing inserted cards from an inclined position to a practically squarely packed position when the case is closed, and a spring disposed between the frame and the case normally holding the frame in a suitably inclined position so as to hold the inserted cards in such inclined shifted position when the case is open. 60 65

4. In a card case of the class described a 70 frame comprising a base bar, side bars and end bars, the side bars being formed to receive the cards inserted in such case side- wise when the case is closed while the end bars have springing capacity for pressing 75 upon the cards endwise in closed and opened position.

5. In a card case of the class described a frame having means for holding cards and having spring members formed so as to shift 80 the frame to an inclined position when the case is open for bringing the cards into a slightly shifted position in relation to each other. 85

In testimony whereof I hereunto affix my signature in the presence of two witnesses.

WILLIAM C. CUTLER.
